(57) **CLAIM**

The ornamental design for a holder for refrigerator of vehicles, as shown and described.

DESCRIPTION

FIG. 1 is a front, right side perspective view of a holder for refrigerator of vehicles showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view with the article shown in use. In FIG. 8, the broken line showing is for the purpose of illustrating environmental structure and forms no part of the claimed design.

1 Claim, 8 Drawing Sheets
